UNITED STATES PATENT OFFICE.

ENOS H. JOHNSON, OF LOS ANGELES, CALIFORNIA.

UNIVERSAL MACHINE VISE.

Application filed April 18, 1923. Serial No. 632,977.

To all whom it may concern:

Be it known that I, ENOS H. JOHNSON, a citizen of the United States of America, residing at Los Angeles, in the county of 5 Los Angeles and State of California, have invented certain new and useful Improvements in Universal Machine Vises, of which the following is a specification.

This invention relates to certain new and 10 useful improvements in universal machine vises especially adapted for use on planer shaper milling machines or drill presses.

An important object of the invention is to provide a device of the above mentioned 15 character that affords proper adjustment for holding material being worked upon at any desired angle.

A further object of the invention is to provide a vise suitable for any kind of bench 20 work, and one that may be employed entirely separate from the universal features of adjustment.

A further object of the invention is to provide a vise with thoroughly practical and 25 reliable pipe jaw attachments which can be applied very quickly and without the use of screws or bolts.

Other objects and advantages of the invention will be apparent during the course 30 of the following description.

In the accompanying drawings forming a part of this specification and in which like numerals are employed to designate like parts throughout the same,

Figure 1 is a top plan view of the assembled vise embodying this invention.

Figure 1^A is a transverse sectional view taken on lines I^A—I^A of Fig. 1.

Figure 2 is a side elevational view of the 40 assembled vise shown in Fig. 1.

Figure 3 is a fragmentary detail view of pipe jaw attachments capable of being positioned upon the jaws of the vise for adapting the same for being employed as a pipe vise.

Figure 4 is a detail view showing in side elevation one of the pipe jaws attached to the inner jaw of the vise,

Figure 5 is a front elevational view, partly in section, of the pipe jaw and vise jaw shown in Fig. 4 positioned upon the jaw carriage of the vise,

Figure 6 is a transverse sectional view showing locking means employed for retaining the base unit and sub-base unit in 50 their desired adjusted positions,

Figure 7 is a vertical sectional view of the locking means shown in Fig. 6,

Figure 8 is a detail vertical sectional view of the outer vise jaw embodying this invention,

Figure 9 is a vertical sectional view, partly in elevation, of the securing means employed for retaining the outer jaw in its desired adjusted position,

Figure 10 shows a removable plate adapted for being positioned upon the vise jaws for allowing square work to be retained within the device in such a position that work may be performed upon the longitudinal edges of the material,

Figure 11 is a top plan view of the vise jaw carriage, and

Figure 12 is an end elevational view of the carriage shown in Fig. 11.

In the drawings, wherein for the purpose of illustration is shown the preferred embodiment of this invention, the numeral 1 designates what I will herein refer to as the base unit, it being adapted for securing to any machine base plate or work bench by means of the slotted lugs 2 as best shown in Figs. 2 and 6. Rotatably connected to the base unit 1 is what I will term a sub-base unit 3 having formed upon its top face spaced inwardly directed guide flanges 4 that are adapted for engaging longitudinally extending grooves 5 formed in the slidably mounted vise jaw carriage 6 which has formed at one end a perpendicularly extending head portion 7 that is provided with a transversely extended threaded bore 8 for a purpose to be described hereafter. Referring particularly to Figs. 1, 5 and 7 wherein there is shown a series of set screws 9 that adjustably engage one of the flanges 4 and are provided for bearing against the gib key 10 for the purpose of retaining the carriage 6 in its adjusted position.

It is to be understood that this vise carriage may be entirely removed from the sub-base unit 3 for the purpose of securing the same directly to a work bench or the like, there being provided clamping bolt engaging slots 11 for this purpose. The vise jaw carriage 6 is further provided with inwardly directed flanges 12 adapted for engaging the outwardly projecting lugs 13 carried by the base of the inner vise jaw 14 which is slidably associated with the said carriage. Threadedly engaging the bore 8

formed in the head portion 7 is a screw 15 that is rotatably connected to the inner jaw 14 by means of the transverse locking pin 16, there being further provided a cross handle 17 for operating the adjusting screw 15. Slidably engaging the carriage 6 is a quick adjustable vise jaw 18 having depending spaced lugs 19 formed on its lower face for engaging the inwardly projecting flanges 12 carried by the carriage to prevent lateral shifting of the said jaw, there being provided a T-bolt 20 having its head portion positioned below the flanges 12 and extending upwardly through the jaw base opening 21 for receiving the locking lever 22 which is retained in position by means of the adjusting nuts 23. By closely examining Figs. 8 and 9 it will be seen that the upper peripheral edge of the opening 21 is provided with camming portions 24 that are to be engaged by the camming surfaces 25 formed upon the lower face of the lever 22 for the purpose of locking the vise jaw 18 in its adjusted position. The vise jaw carriage 6 is further provided with transverse grooves or notches 26 that are adapted for receiving the drop bar 27 carried by the vise jaw 18 and is adapted for use when extra heavy pieces of material are being worked upon.

Referring particularly to Figs. 3 to 5 inclusive and 10 there are shown vise jaw attachments adapted for converting all of the said jaws so that round material may be worked upon while in a vertical or horizontal position and whereby square stock may be held so that longitudinal edges instead of flat surfaces may be conveniently positioned for the mechanic working thereupon. In Fig. 3 there are shown pipe jaw attachments that consist of the single flange pipe engaging jaw 26 and the double flange pipe engaging jaw 27 each having a hook-shaped lug 28 formed upon its upper end and adapted for engaging a notch 29 formed in the vise jaw while a laterally extending lug 30 is formed upon the lower end of each attachment and is adapted for engaging a recess 31 formed in the main vise jaw for preventing lateral movement of the said attachments. It will be seen that these pipe jaws may be very readily applied and removed from the main vise jaws by first positioning the hook-shaped lug 28 in the recess 29 and rocking the lower end of the said attachment towards the base of the vise jaw for positioning the lug 30 within the recess 31, and by reversing the operation the said attachments may be as readily removed. In Fig. 5 there are shown apertures 32 formed in the face of the vise jaw for receiving the pins 33 formed on the attachment shown in Fig. 10, this attachment consisting of plates 34 that are provided with intersecting substantially V-shaped grooves 35 for the purpose of adapt-

ing the vise for retaining round stock in either a vertical or horizontal position.

Referring particularly to Figs. 6 and 7 there is shown means for retaining the sub-base unit 3 in any desired adjusted position in respect to the base unit 1, the said sub-base unit 3 and base unit 1 being of substantially shell formation to provide space for this locking feature of construction. Centrally positioned within the two units and pivotally secured to the base unit 1 by means of the pivot screw 36 is a hub member 37 that is provided with an operating lever 38 which projects outwardly of the said unit, the said hub 37 being provided with radial lugs 39 that are adapted for pivotally supporting the locking links 40 which are provided at their outer ends with diagonal slots 41 for receiving the guiding and adjusting screws 42 which are secured to the base unit 1. It is the purpose of these locking links 40 to project into an annular groove 43 formed in the sub-base unit 3 for the purpose of wedging outwardly against the wall of the sub-base unit to securely bind thereagainst for preventing relative movement between the two units, and by moving the operating lever 38 into its dotted line position as shown in Fig. 6, the locking links 40 will be withdrawn from the annular groove 43 for the purpose of allowing the sub-base unit 3 to be rotated upon the unit 1. There is further provided means for preventing the separation of the two units when the locking links 40 are not engaging the annular groove 43, this means consisting of perpendicularly extending plates 44 that are adjustably clamped to the base unit by means of the screws 45, there being further provided transverse ribs 46 that are adapted for being positioned within the annular groove 43 formed in the sub-base unit 40 when the clamping screws 45 are properly tightened to draw the plate 44 against the walls of the said units. Secured to the inner faces of the plates 44 are spring members 47 that are connected at their opposite ends to pins 48 carried by the floor of the base unit 1, it being seen that these spring elements will withdraw the transverse ribs 46 from the annular groove 43 when the clamping screws 45 are loosened, thereby allowing the removal of the sub-base unit 3 from the base unit 1 when so desired.

It is believed that the formation and relative assembly of the various elements constituting this universal machine vise will be understood from the above detail description, thereby requiring no further description of the same. It is to be understood that the form of this invention herewith shown and described is to be taken as a preferred example of the same, and that various changes in the shape, size, and arrangement

of parts may be resorted to without departing from the spirit of the invention or the scope of the subjoined claims.

Having thus described the invention, I claim:—

1. In a vise of the class described, a base unit, a sub-base unit rotatably secured thereto, means for locking said units in any adjusted position, a vise jaw carriage slidably associated with the sub-base unit, means for retaining said carriage in any adjusted position, a screw adjusted jaw slidably associated with said carriage, a quickly adjustable jaw associated with said carriage and adapted to coact with the first mentioned jaw, and means for clamping the last mentioned jaw to said carriage to retain it in adjusted position.

2. In a vise of the class described, a vise jaw carriage, inwardly directed guide flanges formed on said carriage, a screw actuated jaw associated with said flanges, a second jaw slidably associated with said flanges, and means for locking the second jaw in any desired adjusted position.

3. In a vise of the class described, a vise jaw carriage, inwardly directed guide flanges formed on said carriage, a screw actuated jaw associated with said flanges, a second jaw slidably associated with said flanges, a T-shaped bolt associated with the second jaw and said flanges, and a clamping lever carried by said bolt for locking the second jaw in any adjusted position upon said carriage.

4. In a vise of the class described, a base unit, a sub-base unit rotatably associated therewith, means for locking said units in any adjusted position, and a vise jaw carriage associated with the sub-base unit, said means comprising an annular groove formed in the sub-base unit, locking links carried by the base unit, and an actuating lever for moving said links into engagement with said groove for the purpose specified.

5. In a vise of the class described, a base unit, a sub-base unit rotatably associated therewith, means for locking said units in any adjusted position, and a vise jaw carriage associated with the sub-base unit, said means comprising an annular groove formed in the sub-base unit, a rotatable hub carried by the base unit, locking links connected to said hub, and an actuating lever formed on said hub for moving said links into engagement with said groove for the purpose specified.

6. In a vise of the class described, a vise jaw carriage, inwardly directed guide flanges

formed on said carriage, a screw actuated jaw slidably secured to said flange, a second jaw slidably associated with said flanges, means for preventing lateral relative movement between the second jaw and said carriage, and means for clamping the second jaw to said carriage for preventing sliding movement of the jaw.

7. In a vise of the class described, a base unit having means for permitting it to be secured to a machine base plate, a sub-base unit adjustably secured to the base unit, and a vise jaw carriage adjustably removably secured to the sub-base unit and having means for permitting it to be secured to a work bench independently of the base and sub-base units when removed therefrom.

8. In a vise of the class described, a carriage, a screw actuated jaw associated with said carriage, a quickly adjustable jaw associated with said carriage, means for slidably clamping the last mentioned jaw to said carriage, and additional holding means for reinforcing said clamping means for retaining said quickly adjustable jaw in its desired position.

9. In a vise of the class described, a carriage, inwardly directed side flanges carried by said carriage, a screw actuated jaw associated with said carriage, a quickly adjustable jaw associated with said carriage, said carriage having transversely alined sets of grooves formed in its upper face, means for slidably clamping the quickly adjustable jaw to said carriage, and a drop bar holding means adapted to selectively engage said transversely alined grooves for reinforcing the clamping means employed for holding the quickly adjustable jaw in its proper position.

10. In a vise of the class described, a carriage, inwardly directed flanges carried by the opposite sides of said carriage, said flanges having transversely alined grooves formed in their outer faces, a screw actuated jaw associated with said flanges, a quickly adjustable jaw associated with said carriage, a T-shaped bolt having a clamping lever associated therewith for clamping the quickly adjustable jaw in its proper position upon said carriage, and a drop bar carried by said quickly adjustable jaw adapted to be moved into engagement with said grooves for reinforcing said clamping means for holding said quickly adjustable jaw in its proper position.

In testimony whereof I affix my signature.
ENOS H. JOHNSON.
